[57] CLAIM

The ornamental design for a fluid level probe mounting unit, as shown and described.

DESCRIPTION

FIG. 1 is a perspective view taken from the top, front and left side of a fluid level probe mounting unit showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is a cross sectional view taken on line 8—8 of FIG. 2.
